CONDENSER FOR CLOTHES DRIER

Peter Eduard Geldhof, Benton Harbor, Mich., assignor, by mesne assignments, to Whirlpool Corporation, a corporation of Delaware

Application October 19, 1953, Serial No. 386,925

1 Claim. (Cl. 34—75)

The present invention relates to a condenser for clothes drier and more particularly relates to a condenser for dehumidifying and cleaning air to be heated and circulated into and through a clothes drier or the like.

Although devices incorporating the principles of the present invention are devices of general utility and general applicability, as will be clear from an understanding thereof by reading the following detailed specification and inspecting the drawings, devices incorporating the principles of the present invention are particularly useful in conjunction with clothes driers and the like and particularly useful with combined clothes washers and driers.

Clothes driers generally and clothes driers of size and design for domestic use specifically, having hot air drying systems, include means for heating the air and passing it into the drier and exhausting the spent air from the drier. While hot air is circulating through the drier it picks up moisture and lint from the clothes or other cloth material, objects or the like being dried in the drier.

When this moist air carrying lint or the like is exhausted from the drier, it is necessary to either filter the air to at least remove the lint therefrom or to vent the air to the atmosphere outside of the building containing the drier, or both. Without such external venting, the room in which the drier is situated has the air therein substantially filled with lint. Further, in many instances the room wherein the drier is situated is relatively small or a number of driers are situated there with the result that when air is exhausted from the drier, even with the lint filtered out therefrom, the room is made uncomfortably hot and humid causing working conditions for the operators of the driers to be most disagreeable.

By the present invention these difficulties are substantially obviated and there is provided a new and improved means for removing the moisture and/or lint from the spent air exhausted from the drier. Therefore, an important object of the present invention is to provide means for substantially dehumidifying and substantially cleaning or washing air exhausted from a clothes drier or the like.

Another important object of the present invention is to provide a condenser or the like in combination with a clothes drier or the like, and including an air chamber or channel having a coolant jacket thereabout and means to feed coolant thereto.

Still another object of the present invention is to provide a new and improved condenser for dehumidifying and/or washing or otherwise cleaning air from a clothes drier or the like to substantially remove the moisture and lint therein contained.

Still another object of the present invention is to provide a new and improved condenser for the air system of a hot air drier or the like and including an air channel having heat conductive walls and a coolant jacket thereabout to cool said walls and thereby dehumidify air passing through said air channel.

Still another object of the present invention is to provide a condenser or the like in combination with a com-

2

bined clothes washer and drier unit to substantially dehumidify and clean air exhausted from the drier unit and to feed air to a heating unit prior to repassage of the air into the drier unit.

5 Still other objects, features and advantages of the present invention will readily present themselves from the following detail description of the scope of the present invention and a preferred embodiment thereof, from the claim, and from the accompanying drawings in which 10 there is illustrated a preferred embodiment of the present invention, in which each and every detail shown is fully and completely disclosed, in which like reference numerals refer to like parts, and in which:

Figure 1 is a rear or back side view of a combined 15 washer and drier and condenser incorporating the principles of the present invention and having the back cover removed therefrom and portions of certain parts are broken away to more clearly illustrate certain features thereof; and

20 Figure 2 is a fragmentary sectional view of the condenser from the combined structure of Figure 1 as taken substantially along the line II—II of Figure 1.

The preferred form of the present invention illustrated 25 on the drawings includes a combined washing and drying machine 10 having a washing compartment 11 and a drying compartment 12 which is disposed above the washing compartment 11 and spaced therefrom by a control and drive compartment 13 positioned between the washing and drying compartments 11 and 12. The mechanism is 30 enclosed within a housing or supporting casing 14 including side walls 15 and 16 and extreme top and bottom walls 17 and 18 in addition to an appropriately configured front wall (not shown) and a back wall which has been removed to more clearly illustrate the features 35 of the present invention. The mechanism is further preferably supported above the floor by adjustable legs and feet 19 and 20 which may be adjusted to level the machine as supported above the floor line 21.

The washing compartment 11 contains a suitable 40 clothes washing mechanism or the like which has not been illustrated here since it forms no part of the present invention and in the drawings of Figure 1 is hidden by a washing compartment rear partition wall 22.

After the clothes have been washed and/or rinsed by 45 the washing mechanism in the washing compartment 11, they are removed therefrom and deposited in a drier drum 23 which is rotatably mounted for rotation about a horizontal axis extending from front to rear in the drier compartment 12 and illustrated by the full circle phantom line.

50 A bulkhead 24 substantially encloses the rear portion of the drier drum and drier compartment 12 and the control and operating compartment 13 and is substantially in registration with the partition wall 22 at a junction 25 therebetween. The partition wall 22 and the bulkhead 24 are preferably structural members which aid in supporting the various members and mechanisms of the machine 10.

The drier mechanism is preferably operative to effect 55 drying of the clothes carried in the suitably rotatably supported drum 23 by hot air or the like supplied from a duct or conduit member 26 which includes and contains a suitable air heater arrangement 27. Air from the duct 26 is fed through an aperture 28 in the bulkhead and into the drum 23 preferably through a perforated rear wall on the drum. The duct 26 is joined to the bulkhead 24 so that the passage therethrough mates with the aperture 28 for air inlet into the drier compartment 12 as at 29.

60 As the air circulates through the drier drum 23 and drier compartment 12 over the clothes contained therein it picks up a substantial quantity of moisture and lint 65 and the like from the tumbling cloth articles or the like.

When the hot air is substantially "spent" as it circulates through the drum 23 it is exhausted therefrom again preferably through the perforated rear wall of the drum and through an outlet or exhaust aperture 30 in the bulkhead and into an exhaust duct or conduit or the like 31 which is secured to the bulkhead with its passage in registration with the aperture 30 as at 32.

The impeller 33 draws air through the exhaust duct 31 and forces the same into a condenser 34 which washes, cleans and dehumidifies the air in accordance with the principles of the present invention and directs the air to a clean air feed duct 35 which is in direct communication with the duct 26 containing the heater 27.

The impeller 33 is preferably a centrifugal type fan or air pump or the like which has the air fed substantially axially into the center region thereof where a rotor 36 has a plurality of impeller blades 37 mounted thereon for corotation. The volute shaped housing 38 for the air impeller mechanism is properly proportioned and configurated to direct the air through the above described channels therefor. The rotor and impeller blades are driven by a drive motor or the like 39 which is suitably mounted in the controller and drive section 13 and is coupled to the impeller by a drive belt or the like 40 and appropriate pulleys 41 and 42 suitably secured to the shafts of the motor 39 and rotor 36, respectively. This same belt 40 also engages an idler pulley 43 to drive the same and a shaft 44 to which it is secured. The shaft 44 is suitably supported and journaled within the drive and control compartment 13 and carries additional pulleys 45 thereon for corotation therewith. One of the pulleys 45 is coupled to the drier drum 23 through another belt or the like 46 whereby rotation or power driving of the motor 39 effects rotation of the drum 23 on suitable support members such as a journal or bearing 47 on the bulkhead 24.

By energization of the motor the drum 23 is rotated for tumbling the clothes and the rotor of the fan 33 is driven for driving air through the substantially closed air circulatory system herein above described. As the air from the fan 33 is passed to the condenser 34 it enters an air chamber or air channel 48 from the fan outlet duct 49. While passing through the air chamber 48 of the condenser 34 the air is substantially cooled to dehumidify the same and remove a substantial portion of the moisture therefrom, and washed or cleaned by liquid running through the air.

The air chamber or channel 48 is a substantially hollow flattened duct work or the like having open upper and lower ends 50 and 51 with front and rear walls 52 and side walls 53 (Figure 1) formed of a heat conductive material such as sheet metal or the like which may be galvanized or the like to prevent corrosion thereof when formed of a corrodable material such as iron or steel, or which may be formed of some non-corrodable material. These walls 52 and 53 laterally close the air channel 48 for a substantial distance through the height of the condenser unit 34. Further, the chamber or channel 48 is in substantial registration with the passage in the outlet duct 49 from the exhaust fan.

A coolant jacket or the like 54 surrounds the air channel 48 and is defined by front and rear walls 55 and side walls 56 in addition to the front and rear walls 52 and side walls 53 of the air channel 48. Flanges on the upper and lower ends of the air channel walls, as at 57 and 58, formed either as integral flanges or as angle members or the like secured to the wall members, close the upper and lower ends of the coolant jacket 54 and are substantially sealingly secured to the outer walls 55 and 56 of the coolant jacket to substantially prevent coolant leakage therefrom.

A flanged aperture 59 in the coolant jacket 54 adjacent to the lower flange 58 on the air channel walls 52 mates with a liquid coolant inlet pipe or tube 60 to

provide for admitting liquid coolant into the coolant jacket 54. The joint between the mating flanged aperture 59 and inlet pipe or tube 60 is preferably substantially sealed to prevent coolant leakage therebetween.

5 Liquid coolant such as cold water or the like is controllably supplied from any convenient source such as a household pressurized supply through the inlet pipe or tube 60 and controlled by a control valve 61 or by any other convenient control means such as a valve which may be located at the front of the machine or tied in with controls for the drier so that liquid coolant flows while the drier is operating. The liquid coolant flows into the coolant jacket 54 and fills the coolant chamber defined by the coolant jacket walls to a height substantially close to the upper flanges 57 on the air channel walls where apertures 62 near the top of the air channel walls admit the liquid coolant into the air channel to project in streams across the channel covering substantially the entire area thereof, as illustrated by the location of the apertures 62 in Figure 2.

20 Liquid coolant flows through the coolant jacket 54 and cools the walls 52 and 53 to effect a substantial cooling of the air passing through the air channel or chamber 48 thereby reducing its ability to carry water vapor or the like and thus condensing a substantial portion of water vapor, etc. therefrom. As the liquid flows through the apertures 62 into the air channel 48 it is still cold and further aids in cooling the air passing through the channel as exhausted from the drier mechanism. In addition, the cold water or the like washes and cleans the air and catches the lint and dust in the air to remove the lint and dust and the like from the air.

25 As the air and coolant flows from the bottom 51 of the air channel 48 it enters into the condenser exhaust and drain chamber 63 where an aperture or the like 64 in one of the side walls 56 of the condenser is in registration with the drier air duct 35. The air flowing into the duct 35 is thus substantially dry clean air which has been washed and cleaned and dehumidified in the condenser 34 in accordance with the principles of the present invention. The liquid coolant entering the condenser discharge or exhaust chamber 63 falls to a tapered or inclined bottom 65 where it runs to a drain 66. The bottom 65 of the condenser drain and exhaust chamber 63 is preferably formed in an obtuse angle with its apex substantially at the center of the condenser to drain the liquid coolant carrying the lint, dust and the like toward the drain 66. The liquid coolant carrying the lint and dust is removed from the drain 66 by a pump 67 or like mechanism and fed to an outlet 68 for discharge to any convenient drainage or sewage system.

30 The pump 67 may be of any convenient form of pump preferably such as a centrifugal pump or the like and is driven by a pulley or the like 69 fixed to the pump shaft for corotation therewith and coupled to a pulley on the main idler shaft 44 by a belt or the like 70.

35 From the foregoing it will be readily observed by the principles of the present invention that there is provided a new and improved condenser of generally utility but particularly adapted for combination with a combined washer and hot air drier or the like. It will also be observed that numerous modifications and variations may be effected without departing from the true spirit and scope of the novel concepts and principles of the present invention. I, therefore, intend to cover all such modifications and variations as fall within the true spirit and scope of the novel concepts of the principles of my invention.

40 I claim as my invention:

A clothes drier comprising a rotary clothes drum rotatably housed in a cabinet, a substantially closed air circulation conduit in said cabinet leading from the drum and returning thereto, an air washing and cooling chamber having vertical walls defining a vertical air passage-

way in said air circulating conduit, said passageway being unobstructed, a coolant jacket having enclosing walls and closed at its upper and lower ends with at least one of the walls of the jacket being a vertical wall of the cooling chamber, orifices adjacent the upper end of the common vertical wall of the jacket for the projection of substantially horizontal streams of coolant to cover substantially the entire area of the cooling chamber to engage and cool and wash the air, means for forcing the air through said conduit into the top of the air chamber and out of the bottom, and means for supplying coolant

under pressure to the jacket adjacent the lower end thereof.
